PRESSURE FLUID MOTOR

Elmer G. Gartin, Claremont, N. H., assignor to
Sullivan Machinery Company, a corporation of
Massachusetts

Application July 30, 1940, Serial No. 348,428

20 Claims. (CL. 121—19)

This invention relates to pressure fluid motors, and more particularly to improvements in the fluid distribution means for a pressure fluid motor of the reciprocating piston type.

An object of this invention is to provide an improved pressure fluid motor. Another object is to provide improved fluid distribution means embodying improved fluid distributing valve means whereby the flow of pressure fluid to the motor cylinder is controlled in an improved manner. A further object is to provide an improved fluid distributing valve means of the double-valve type, one valve individual to the flow of fluid to each end of the motor cylinder, whereby a more efficient motor is obtained. Yet another object is to provide an improved double-valve fluid distribution means having improved means for positively throwing the distributing valves into their different operating positions. A still further object is to provide an improved auxiliary exhaust means for one of the pressure areas on the rear valve whereby throwing of the rear valve is substantially delayed. Other objects and advantages of the invention will, however, hereinafter more fully appear.

In the accompanying drawings there are shown for purposes of illustration two forms which the invention may assume in practice.

In these drawings:

Fig. 1 is a view in longitudinal vertical section through a pressure fluid motor constructed in accordance with an illustrative embodiment of the invention.

Figs. 2 and 3 are views similar to Fig. 1, showing the distributing valves and motor piston in different operating positions.

Fig. 4 is an end elevational view of one of the fluid distributing valves.

Fig. 5 is a side elevational view of the distributing valve shown in Fig. 4.

Fig. 6 is an enlarged fragmentary sectional view taken in the plane of Fig. 1, illustrating the improved valve means.

Fig. 7 is a view in longitudinal vertical section taken through a pressure fluid motor constructed in accordance with another illustrative embodiment of the invention.

Figs. 8 and 9 are views similar to Fig. 7, showing the distributing valves and motor piston in different operating positions.

Fig. 10 is an end elevational view of the rear distributing valve.

Fig. 11 is a side elevational view of the valve shown in Fig. 10.

Fig. 12 is an enlarged fragmentary sectional

view taken in the plane of Fig. 7, illustrating the modified valve means.

In both illustrative embodiments of the invention the improved fluid distribution means is shown embodied in a pressure fluid motor of the reciprocating piston, impact type especially designed for use in hammer drilling tools. It will be evident, however, that various features of the invention may be incorporated in pressure fluid motors of various other types.

In the embodiment of the invention shown in Figs. 1 to 6, inclusive, the pressure fluid motor with which the improved fluid distribution means is associated, comprises a motor cylinder 1 having a bore 2 containing a reciprocating motor piston 3. The motor piston is, in this instance, in the form of a hammer and is adapted to deliver impact blows through a tappet 4 to the shank 5 of a suitable working implement. The cylinder has a front head 6 having a bore in which the tappet is reciprocably mounted, and the shank of the working implement projects within the head bore in a position to receive the impact blows transmitted thereto by the tappet. The cylinder has a rear head plate 7 arranged in a bore 8 in a rear head block 9, the head block bore also receiving the rear end of the motor cylinder, in the manner shown. Also arranged in the block bore is a valve block 10 abutting the rear head plate, while a cover plate 11 also arranged in the head block bore abuts the rear face of the valve block. The front head and rear head block are suitably secured to the motor cylinder, and the parts 7, 10 and 11 are clamped in position against the rear end of the cylinder by the rear head block. The parts 7, 10 and 11 cooperate to form a valve chamber 12 in which a pair of cooperating, relatively movable, aligned fluid distributing valves 13 and 14 are reciprocably mounted. The valve chamber has uniform end bores 15 and 16 and an intermediate reduced bore 17, the latter being formed in a partition 18. The valves are identical in design and are preferably of the tubular sleeve type and respectively have inner sleeve-like body portions 19 and 20 slidably fitting the intermediate reduced bore 17, and outer sleeve-like portions 21 and 22 slidably fitting the bores 15 and 16, the outer portions 21, 22 being connected by radial flanges 23 and 24 to the inner valve bodies. Extending inwardly from each of the valve bodies, substantially midway between the valve extremities, are internal annular flanges 25 and 26, while projecting from the remote faces of the valves are annular projec-

tions 27 and 28 having seating surfaces 29 and 30 adapted to seat against plane seat surfaces formed on the plates 11 and 7 respectively at the opposite ends of the valve chamber. The inner sleeve-like valve bodies 19 and 20 project within the partition bore 17 inwardly toward one another, and the adjacent end faces of the valves are adapted to abut one another in certain valve positions. The plates 11 and 7 have inwardly projecting circular projections 31 and 32, and the bores within the outer sleeve-like portions 21, 22 of the valves slidably engage the exterior peripheries of these projections. The plates 11 and 7 have axial circular projections 33 and 34 formed on their inner faces inwardly of the circular projections 31 and 32 respectively, and these latter projections extend axially within the valves so that the inner peripheries of the internal valve flanges 25, 26 respectively cooperate with the exterior peripheries of the projections to provide restricted clearance spaces 35 and 36 for metering purposes, in a well known manner. The valves cooperate to provide an internal chamber 37 to which pressure fluid may be conducted from any suitable source through a supply passage 38 communicating with a supply chamber 39 formed in the rear head block, and an axial passage 40 in the cover plate 11 connects the chamber 39 with the internal valve chamber 37. The passage 40 extends centrally through the axial circular projection 33. Communicating with the valve chamber at the forward side of the front valve 14 are fluid distribution passages 41 for conducting pressure fluid to the rear end of the cylinder bore at the rear side of the motor piston. Fluid distribution passages 42 communicate with the valve chamber at the rear side of the rear valve 13 for conducting pressure fluid to the front end of the cylinder bore at the front side of the motor piston. A throwing passage 43 communicates with the rear end of the valve chamber bore 16 at the rear side of the front valve flange 24, and a port 44 connects this throwing passage with the cylinder bore. A port 45 connects a throwing passage 46 with the front end of the valve chamber bore 15 at the front side of the rear valve flange 23, and this throwing passage communicates with the cylinder bore through a port 47. Passages 48 in the partition 18 connect the adjacent ends of the valve chamber bores 15 and 16 at the inner sides of the valve flanges 23 and 24. Passages 49 and 50 respectively connect annular grooves or recesses 51 and 52, communicating with the valve chamber bores 15 and 16 at the remote ends of the valves, with a recess 53 which is in turn connected to atmosphere through vent passages 54. The sleeve-like outer portion 21 of the rear valve 13 is preferably perforated by a series of radial apertures 55 for connecting the bore of the sleeve-like portion at the rear side of the valve flange with the rear groove 51. The front valve has its sleeve-like portion 22 perforated by a series of apertures in a like manner, but these apertures are maintained blanked off by the walls of the bore 16. By providing apertures in both valves, the valves are made interchangeable without affecting their operating functions. If desired, however, the apertures in both valves may effect venting and at that time the front groove 52 would naturally be of the same width as the rear groove, instead of narrower as shown. Communicating with the cylinder bore midway

between the ends thereof is a piston-controlled exhaust groove 56 connected to atmosphere through a passage 57 and slots 58.

The general mode of operation of the pressure fluid motor described above is as follows. When the parts are in the position shown in Fig. 1, pressure fluid may flow from the supply passage 38, chamber 39 and axial passage 40 to the pressure chamber 37 within the valves 13, 14. The valves are at that time in their rearmost positions with the front valve 14 abutting the rear valve 13, and the effective rear pressure area of the rear valve is connected to atmosphere through ports 55, groove 51, passage 49, recess 53 and vent passages 54. Pressure fluid acting on the front face of the front valve holds the rear valve in its closed position. Pressure fluid may flow from the internal fluid chamber 37 within the valves, through the restricted clearance space 36, past the front face of the front valve flange 24 and through distribution passages 41 to the rear end of the cylinder bore at the rear side of the motor piston, the fluid acting on the rear pressure area of the piston to move the latter forwardly to effect its working stroke. As the piston moves forwardly, its leading edge first covers the exhaust groove 56, and then its following edge uncovers the port 44, admitting pressure fluid from the rear end of the cylinder bore through the throwing passage 43 to the rear face of the front valve flange 24 to throw the front valve 14 forwardly to its position shown in Fig. 2. A portion of the throwing pressure will pass through passages 48 and act on the front surface of the flange 23 of the rear valve 13 to hold the latter closed. Thus, at this time both valves are closed so that the flow of pressure fluid to the cylinder bore is momentarily completely cut off. As the piston continues to move forwardly, the leading edge of the motor piston overruns the port 47 and thereafter the following edge of the piston uncovers the exhaust groove 56, connecting the rear end of the cylinder bore to exhaust. As the piston approaches the end of its forward stroke, the fluid trapped in the front end of the cylinder bore is compressed, and this compression pressure, a portion of which is vented through ports 55, passage 49, chamber 53 and vents 54, so as to delay rear valve opening, acts through the distributing passages 42 on the rear face of the flange 23 of the rear valve 13 to throw the latter forwardly into its position shown in Fig. 3. It may be noted that uncovering the exhaust further reduces pressure acting on the forward face of the flange 23 of the valve 13. The valves 13 and 14, after valve 13 is thrown forwardly, are both in their foremost positions, with the rear valve 13 abutting the front valve 14 to hold the latter closed, and the forward end of the outer valve sleeve 22 of the front valve is connected to atmosphere through groove 52, passage 50, recess 53 and vent passages 54. Pressure fluid is then admitted to the front end of the cylinder bore at the front side of the motor piston through the valve chamber 37, through the restricted clearance space 35, past the rear face of the rear valve and through the distribution passages 42, the pressure fluid acting on the front pressure area of the motor piston to move the latter rearwardly to effect its return stroke. As the piston moves rearwardly from the position shown in Fig. 3, the leading edge of the piston first overruns the exhaust

groove 56 and thereafter the following edge of the piston uncovers the port 47 of the throwing passage 46, admitting pressure fluid from the front end of the cylinder bore to the pressure area on the front face of the flange 23 of the rear valve 13 to effect throwing of the latter into its rearmost closed position, as shown in Fig. 2, and a part of the fluid passes forwardly through passages 48 to hold the front valve closed. At this time both valves are closed so that the flow of pressure fluid to the cylinder bore is momentarily completely cut off. As the piston continues to move rearwardly, the fluid trapped within the rear end of the cylinder bore is compressed, and this compression pressure acts through the distribution passages 41 on the front face of the flange 24 of the front valve 14 to throw the latter rearwardly into its rearmost position, as shown in Fig. 1, in abutting engagement with the rear valve. The operations above described are rapidly repeated during normal running of the motor.

By the provision of the auxiliary venting ports 55 for the rear side of the flange of the rear valve, opening of the latter is substantially delayed, resulting in a more effective and unopposed action of the pressure fluid in the rear end of the cylinder bore and a more effective piston blow. While a similar auxiliary exhaust might be employed for the front valve, it is considered unnecessary since substantial cushioning of the piston as it approaches the end of its return stroke is desirable. When the compression pressure is built up by the piston to a predetermined degree within the front end of the cylinder bore as the piston approaches the end of its forward working stroke, the rear valve is quickly thrown. It may also be noted that the constant venting of the areas on the ends of the outer sleeve-like portions 21 and 22 will result in sharper, cleaner valve throwing by the pressures acting on the adjacent faces of the flanges 23 and 24.

In the embodiment of the invention shown in Figs. 7 to 12, inclusive, the cylinder and piston structure is similar to that above described, the primary difference residing in the valve means for controlling the supply of pressure fluid to the motor cylinder. Arranged in the bore 8' of the rear head block 9' and abutting the rear end of the cylinder is a rear head plate 60, and also arranged in the block bore and abutting the rear face of the head plate is a valve block 61. A cover plate 62, also arranged in the block bore, abuts the rear face of the valve block, and interposed between the cover plate and the rear wall of the head block bore is a plate 63. The latter plate 62 has an integral tube 64 passing centrally through the cover plate and valve block and having its forward portion fitted tightly within an axial bore 65 in the rear head plate 60. The parts 60, 61 and 62 cooperate to form a valve chamber 68 in which a pair of cooperating, relatively movable, alined fluid distributing valves 67 and 68 are reciprocably mounted. The valve chamber has uniform end bores 69 and 70 and an intermediate reduced bore 71, the latter being formed in a partition 72. The valves are herein preferably of the sleeve type and have sleeve-like bodies 73 and 74 arranged in sliding telescopic relation, and the body of the rear valve slidingly fits the intermediate bore 71. The valve bodies have near their remote ends annular flanges 75 and 76 which at their exterior peripheries slidingly fit the end valve chamber bores 69 and 70. The 75

plates 62 and 60 have inwardly directed circular projections 77 and 78, and the valves 67 and 68 have internal annular flanges 79 and 80 which cooperate with these projections to provide restricted clearance spaces 81 and 82 for metering purposes. Projection from the remote end faces of the valves are circular ledges 83 and 84 having end seating surfaces adapted to seat against plane seat surfaces on the plates 60 and 62 at the opposite ends of the valve chamber. The tube 64, integral with the plate 63, has its bore connected with the supply chamber 39, and ports 85 in the tube connect the tube bore with the pressure chamber 86 within the valves. Fluid distribution passages 41' connect the front bore 70 at the front side of the front valve 68 with the rear end of the cylinder bore, while fluid distribution passages 42' connect the rear valve bore 69 at the rear side of the rear valve 67 with the front end of the cylinder bore at the front side of the motor piston. A throwing passage 43' communicates with the valve bore 70 at the rear side of the flange of the front valve, while a throwing passage 46' communicates with the rear valve bore 69 at the front side of the rear valve flange, and these throwing passages communicate with the cylinder bore through ports 44' and 47' respectively. Passages 48' in the partition 72 connect the adjacent ends of the valve chamber bores 69 and 70 at the inner sides of the external valve flanges 75 and 76. Communicating with the cylinder bore midway between the ends thereof is a piston-controlled exhaust groove 56 connected to atmosphere through a passage 57 and slots 58. Exhaust passages 87 and 88 connect the adjacent ends of the valve bores 69 and 70 at the inner faces of the valve flanges with the atmosphere.

The general mode of operation of this modified form of pressure fluid motor is as follows. When the parts are in the position shown in Fig. 7, pressure fluid may flow from the supply passage 38, chamber 39, the bore of the tube 64 and ports 85 to the pressure chamber 86 within the distributing valves 67 and 68. The valves are at that time in their rearmost positions with the front valve abutting the rear valve, and the effective rear pressure area on the forward face of the external flange of the rear valve is connected to exhaust, as is also the rearward face of the external flange of the valve 68. Pressure fluid may flow from the pressure chamber within the valves through the restricted clearance space 82, through the valve chamber past the forward face of the front valve and through the distribution passages 41' to the rear end of the cylinder bore at the rear side of the motor piston, the pressure fluid acting on the rear pressure area of the motor piston to move the latter forwardly to effect its working stroke. The pressure fluid acting on the forward pressure area of the front valve at that time holds the rear valve in its closed position. As the piston moves forwardly, its leading face covers the exhaust groove 56, and then its following edge uncovers the port 44', admitting pressure fluid from the rear end of the cylinder bore through the throwing passage 43' to the rear face of the external flange 76 of the front valve 68 to throw the latter forwardly to its closed position shown in Fig. 8. The time of throwing will be somewhat modified by the venting of a part of the throwing fluid through the passage 88 and through the passages 48' and 87; and the fluid which acts to close the

valve 68 will also aid in maintaining the valve 67 in closed position. At this time both valves are closed, so that the flow of pressure fluid to the cylinder bore is momentarily completely cut off. The leading edge of the piston then overruns the port 47' and thereafter the following edge of the piston uncovers the exhaust groove 56, connecting the rear end of the cylinder bore to exhaust. As the piston approaches the end of its forward stroke, the fluid trapped in the front end of the cylinder bore is compressed, and this compression pressure acts through the distribution passages 42' on the rear face of the external flange 75 of the rear valve 67 to throw the latter forwardly to its position shown in Fig. 9. When the valves are in the position shown in Fig. 9, the rear valve abuts the front valve to hold the latter in its closed position and the effective rear pressure area on the external flange of the front valve is connected to exhaust through the exhaust passage 38. Pressure fluid is then admitted to the front end of the cylinder bore at the forward side of the piston through the internal valve chamber 86, through the restricted clearance space 81, through the valve chamber past the rear face of the rear valve 67 and through the passages 42', the pressure fluid acting on the front pressure area of the motor piston to move the latter rearwardly to effect its return stroke. The pressure fluid acting on the rear face of the rear valve at that time holds the front valve in its closed position. The front face of the external flange of the rear valve and, though it is not of moment at the time, the rear face of the external flange of the front valve, are then both vented. As the piston moves rearwardly from the position shown in Fig. 9, the leading edge of the piston first overruns the exhaust groove 56 and thereafter the following edge of the piston uncovers the port 47' of the throwing passage 46', admitting pressure fluid from the front end of the cylinder bore to the pressure area at the forward face of the external flange 75 of the rear valve 67 to effect throwing of the latter into its rearmost closed position shown in Fig. 8. The time of throwing of the valve 67 will be somewhat modified by the partial venting of the throwing fluid, in a manner similar to that described with respect to the closing of the front valve 68; and both valves will be subjected to a holding action by the pressure through the passage 46'. At this time both valves are closed so that the flow of pressure fluid to the cylinder bore is momentarily completely cut off. As the piston continues to move rearwardly, the fluid trapped within the rear end of the cylinder bore is compressed, and this compression pressure acts through the distribution passages 41' on the front face of the external flange 76 of the front valve 68 to throw the latter rearwardly into its rearmost position shown in Fig. 7, in abutting engagement with the rear valve. As the piston nears the rear end of its stroke, the exhaust groove 56 is uncovered. The operations above described are rapidly repeated during normal running of the motor.

It will be noted that in the modified form of construction, auxiliary exhaust means is provided for both valves, so that a substantial delay in the throwing of both valves is obtained. If desired, however, the auxiliary exhaust passage for the rear valve may be omitted, with, if needed, a restriction of communication through the passages 48', if more effective cushioning of the

motor piston during its return stroke appears necessary.

As a result of this invention it will be noted that an improved pressure fluid motor is provided having improved fluid distribution means whereby pressure fluid is distributed to the motor cylinder in a novel and more effective manner. It will further be evident that by the provision of the improved fluid distributing valve means embodying cooperating, relatively movable, fluid distributing valves for effecting the control of the flow of pressure fluid to the motor cylinder, not only are the smoothness and efficiency of the operation of the motor improved, but also a more powerful hammer blow is obtained. It will further be evident that by the improved novel valve design embodying a pair of cooperating distributing valves, one individual to the control of flow to each end of the motor cylinder, control of flow of pressure fluid to the motor cylinder is not only improved, but also, due to the symmetry in design of valves having like operating functions, reversal of the valves is possible, thereby eliminating the possibility of improper assembling of the valves. Also by the provision of the improved valve throwing means embodying the auxiliary exhaust means, the valves are thrown into their different operating positions in an improved and more positive manner.

In both main forms of the invention that have been disclosed for purposes of illustration, it will be noted that there is at least one passage leading from the cylinder bore and having its communication with the latter piston-controlled and, in certain piston positions, connected with the exhaust groove 56 through the cylinder bore, which passage at its other end communicates with a valve throwing area which has provided for it another vent or exhaust connection independent of the motor piston.

Other advantages of the invention in addition to those hereinabove noted will be clearly apparent to those skilled in the art.

While there are in this application specifically described two forms which the invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. In a pressure fluid motor, the combination comprising a cylinder, a piston reciprocable in said cylinder, and fluid distribution means for the motor including means providing a pair of aligned valve-receiving bores, fluid distribution passages leading respectively from said bores to the opposite ends of said cylinder, a pressure fluid supply, a pair of cooperating fluid distributing valves arranged in said bores, said valves being relatively movable and adapted to abut one another in certain positions thereof, said valves controlling the flow of pressure fluid from said supply to said passages respectively, means for throwing said valves into their different operating positions including throwing passages communicating with said bores and controlled by said piston for subjecting pressure areas on said valves to valve throwing pressures, certain pressure areas on said valves being connectible to exhaust through said distribution passages under the control of said piston, and auxiliary exhaust means

for one of said valves for substantially delaying the throwing of said latter valve.

2. In a pressure fluid motor, the combination comprising a cylinder, a piston reciprocable in said cylinder, and fluid distribution means for the motor including a piston-controlled cylinder exhaust, means providing a pair of aligned valve-receiving bores, fluid distribution passages leading respectively from said bores to the opposite ends of said cylinder, a pressure fluid supply, a pair of cooperating fluid distributing valves arranged in said bores, said valves being relatively movable and adapted to abut one another in certain positions thereof, said valves controlling the flow of pressure fluid from said supply to said passages respectively, means for throwing said valves into their different operating positions including throwing passages communicating with said bores and controlled by said piston for subjecting pressure areas on said valves to valve throwing pressures, certain pressure areas on said valves being connectible to exhaust through said distribution passages under the control of said piston, and auxiliary exhaust means for one of said valves and controlled by the latter for substantially delaying the throwing of said latter valve.

3. In a pressure fluid motor, the combination comprising a cylinder, a piston reciprocable in said cylinder, and fluid distribution means for the motor including a piston-controlled cylinder exhaust, means providing a pair of aligned valve-receiving bores, fluid distribution passages leading respectively from said bores to the opposite ends of said cylinder, a pressure fluid supply, a pair of cooperating fluid distributing valves arranged in said bores, said valves being relatively movable and adapted to abut one another in certain positions thereof, said valves controlling the flow of pressure fluid from said supply to said passages respectively, means for throwing said valves into their different operating positions including throwing passages communicating with said bores and controlled by said piston for subjecting pressure areas on said valves to valve throwing pressures, certain pressure areas on said valves being connectible to exhaust through said distribution passages under the control of said piston, and auxiliary exhaust means for one of said valves and controlled by the latter for substantially delaying the throwing of said latter valve, said auxiliary exhaust means including ports formed in said valve whereby movement of said valve into a certain position effects exhausting to atmosphere of one of the pressure areas thereon.

4. In a pressure fluid motor, the combination comprising a cylinder, a piston reciprocable in said cylinder, and fluid distribution means for the motor including a piston-controlled cylinder exhaust, means providing a pair of aligned valve-receiving bores, fluid distribution passages leading respectively from said bores to the opposite ends of said cylinder, a pressure fluid supply, a pair of cooperating fluid distributing valves arranged in said bores, said valves being relatively movable and arranged in aligned end abutting relation whereby said valves abut one another in certain positions thereof, said valves controlling the flow of pressure fluid from said supply to said passages respectively, means for throwing said valves into their different operating positions including throwing passages communicating with said bores and controlled by said piston for subjecting said valves to valve throwing pressures,

certain pressure areas on said valves being connectible to exhaust through said distribution passages under the control of said piston, and auxiliary exhaust means for one of said valves for substantially delaying the throwing of said latter valve.

5. In a pressure fluid motor, the combination comprising a cylinder, a piston reciprocable in said cylinder, and fluid distribution means for the motor including means providing a pair of aligned valve-receiving bores, fluid distribution passages leading respectively from said bores to the opposite ends of said cylinder, a pressure fluid supply, a pair of cooperating fluid distributing valves of the sleeve type having sleevelike bodies, outer sleevelike portions and flanges projecting from said bodies for connecting said outer portion to said bodies, said outer portions respectively slidingly fitting said bores, said valves being relatively movable and adapted to abut one another in certain positions thereof, and said valves controlling the flow of pressure fluid from said supply to said passages respectively, and means for throwing said valves into their different operating positions including throwing passages respectively communicating with said bores at the inner sides of said valve flanges and controlled by said piston.

6. In a pressure fluid motor, the combination comprising a cylinder, a piston reciprocable in said cylinder, and fluid distribution means for the motor including means providing a pair of aligned valve-receiving bores, fluid distribution passages leading respectively from said bores to the opposite ends of said cylinder, a pressure fluid supply, a pair of cooperating fluid distributing valves of the sleeve type having sleevelike bodies arranged in sliding telescopic relation, outer sleevelike portions and flanges projecting from said bodies for connecting said outer portions to said bodies, said outer portions respectively slidingly fitting said bores, said valves being relatively movable and adapted to abut one another in certain positions thereof, and said valves controlling the flow of pressure fluid from said supply to said passages respectively, and means for throwing said valves into their different operating positions including throwing passages respectively communicating with said bores at the inner sides of said valve flanges and controlled by said piston.

7. In a pressure fluid motor, the combination comprising a cylinder, a piston reciprocable in said cylinder, and fluid distribution means for the motor including means providing a pair of end valve-receiving bores and an intermediate reduced bore connecting said end bores, fluid distribution passages leading respectively from said end bores to the opposite ends of said cylinder, a pressure fluid supply, a pair of cooperating fluid distributing valves of the sleeve type having sleevelike bodies slidingly fitting said reduced intermediate bore and external flanges having integral sleevelike outer portions slidingly fitting said end bores, said valves being relatively movable and adapted to abut one another in certain positions thereof, and said valves controlling the flow of pressure fluid from said supply to said passages respectively, and means for throwing said valves into their different operating positions including throwing passages respectively communicating with said end bores at the inner sides of said valve flanges and controlled by said piston for subjecting pressure areas on said valves to valve throwing pressures, said distribu-

tion passages communicating with said end bores at the remote sides of said valve flanges whereby said valves are thrown in one direction by compression pressure built up in said distribution passages by the motor piston.

8. In a pressure fluid motor, the combination comprising a cylinder, a piston reciprocable in said cylinder, and fluid distribution means for the motor including means providing a pair of end valve-receiving bores and an intermediate reduced bore connecting said end bores, fluid distribution passages leading respectively from said end bores to the opposite ends of said cylinder, a pressure fluid supply, a pair of cooperating fluid distributing valves of the sleeve type having sleeve-like bodies slidably fitting said reduced intermediate bore and external flanges having outer portions slidably fitting said end bores, said valves being relatively movable and adapted to abut one another in certain positions thereof, and said valves controlling the flow of pressure fluid from said supply to said passages respectively, means for throwing said valves into their different operating positions including throwing passages respectively communicating with said end bores at the inner sides of said valve flanges and controlled by said piston for subjecting pressure areas on said valves to valve throwing pressures, said distribution passages communicating with said end bores at the remote sides of said valve flanges whereby said valves are thrown in one direction by compression pressure built up in said distribution passages by the motor piston, and passage means for connecting said end bores at the inner sides of said valve flanges into constant communication.

9. In a pressure fluid motor, the combination comprising a cylinder, a piston reciprocable in said cylinder, and fluid distribution means for the motor including a piston-controlled cylinder exhaust, means providing a pair of end valve-receiving bores and an intermediate reduced bore connecting said end bores, fluid distribution passages leading respectively from said end bores to the opposite ends of said cylinder, a pressure fluid supply, a pair of cooperating fluid distributing valves of the sleeve type having sleeve-like bodies slidably fitting said reduced intermediate bore and external flanges having outer portions slidably fitting said end bores, said valves being relatively movable and adapted to abut one another in certain positions thereof, and said valves controlling the flow of pressure fluid from said supply to said passages respectively, means for throwing said valves into their different operating positions including throwing passages respectively communicating with said end bores at the inner sides of said valve flanges and controlled by said piston for subjecting pressure areas on said valves to valve throwing pressures, said distribution passages communicating with said end bores at the remote sides of said valve flanges whereby said valves are thrown in one direction by compression pressure built up in said distribution passages by the motor piston, certain pressure areas on said valves being connectible to exhaust through said distribution passages under the control of said piston, and auxiliary exhaust means for a pressure area on one of said valves whereby throwing of said latter valve is substantially delayed.

10. In a pressure fluid motor, the combination comprising a cylinder, a piston reciprocable in said cylinder, and fluid distribution means for the

motor including a piston-controlled cylinder exhaust, means providing a pair of end valve-receiving bores and an intermediate reduced bore connecting said end bores, fluid distribution passages leading respectively from said end bores to the opposite ends of said cylinder, a pressure fluid supply, a pair of cooperating fluid distributing valves of the sleeve type having sleeve-like bodies slidably fitting said reduced intermediate bore and external flanges having outer portions slidably fitting said end bores, said valves being relatively movable and adapted to abut one another in certain positions thereof, and said valves controlling the flow of pressure fluid from said supply to said passages respectively, means for throwing said valves into their different operating positions including throwing passages respectively communicating with said end bores at the inner sides of said valve flanges and controlled by said piston for subjecting pressure areas on said valves to valve throwing pressures, said distribution passages communicating with said end bores at the remote sides of said valve flanges whereby said valves are thrown in one direction by compression pressure built up in said distribution passages by the motor piston, passage means for connecting said end bores at the inner sides of said valve flanges into constant communication, certain pressure areas on said valves being connectible to exhaust through said distribution passages under the control of said piston, and auxiliary exhaust means for a pressure area on one of said valves whereby throwing of said latter valve is substantially delayed.

11. In a pressure fluid motor, the combination comprising a cylinder, a piston reciprocable in said cylinder, and fluid distribution means for the motor including means providing a pair of end valve-receiving bores and an intermediate reduced bore connecting said end bores, fluid distribution passages leading respectively from said end bores to the opposite ends of said cylinder, a pressure fluid supply, a pair of cooperating fluid distributing valves of the sleeve type having sleeve-like bodies arranged in sliding telescopic relation, with the larger one of said valve bodies slidably fitting said intermediate reduced bore, sleeve-like outer portions and external flanges projecting from said valve bodies for connecting said outer portions to said bodies, said outer portions slidably fitting said end bores, said valves being relatively movable and adapted to abut one another in certain positions thereof, and said valves controlling the flow of pressure fluid from said supply to said passages respectively, and means for throwing said valves into their different operating positions including throwing passages respectively communicating with said end bores at the inner sides of said valve flanges and controlled by said piston for subjecting pressure areas on said valves to valve throwing pressures, said distribution passages communicating with said end bores at the remote sides of said valve flanges whereby said valves may be thrown in one direction by compression pressure built up in said distribution passages by the motor piston.

12. In a pressure fluid motor, the combination comprising a cylinder, a piston reciprocable in said cylinder, and fluid distribution means for the motor including a piston-controlled cylinder exhaust, means providing a pair of alined valve-receiving bores, fluid distribution passages leading respectively from said bores to the opposite ends of said cylinder, a pressure fluid supply, a pair of cooperating fluid distributing valves

arranged in said bores, said valves being relatively movable and adapted to abut one another in certain positions thereof, said valves cooperating to provide an internal fluid supply chamber therein, said fluid supply constantly communicating with said internal chamber, and said valves controlling the flow of pressure fluid through said chamber to said passages respectively, means for throwing said valves into their different operating positions including passages communicating with said bores and controlled by said piston for subjecting pressure areas on said valves to valve throwing pressures, certain pressure areas on said valves being connectible to exhaust through said distribution passages under the control of said piston, and auxiliary exhaust means for a pressure area of one of said valves for substantially delaying the throwing of said latter valve.

13. In a pressure fluid motor, the combination comprising a cylinder, a piston reciprocable in said cylinder, and fluid distribution means for the motor including a piston-controlled cylinder exhaust, means providing a pair of alined valve-receiving bores, fluid distribution passages leading respectively from said bores to the opposite ends of said cylinder, a pressure fluid supply, a pair of cooperating fluid distributing valves arranged in said bores, said valves being relatively movable and adapted to abut one another in certain positions thereof, said valves cooperating to provide an internal fluid supply chamber therein, said fluid supply constantly communicating with said internal chamber, and said valves controlling the flow of pressure fluid through said chamber to said passages respectively, said valves cooperating with means for providing a restricted flow of fluid from said chamber to said passages, means for throwing said valves into their different operating positions including passages communicating with said bores and controlled by said piston for subjecting pressure areas on said valves to valve throwing pressures, certain pressure areas on said valves being connectible to exhaust through said distribution passages under the control of said piston, and auxiliary exhaust means for a pressure area of one of said valves for substantially delaying the throwing of said latter valve.

14. In a pressure fluid motor, the combination comprising a cylinder, a piston reciprocable in said cylinder, and fluid distribution means for the motor including a piston-controlled cylinder exhaust, means providing a pair of alined valve-receiving bores, fluid distribution passages leading respectively from said bores to the opposite ends of said cylinder, a pressure fluid supply, a pair of cooperating fluid distributing valves arranged in said bores, said valves being relatively movable and adapted to abut one another in certain positions thereof, said valves controlling the flow of pressure fluid from said supply to said passages respectively, means for throwing said valves into their different operating positions including throwing passages communicating with said bores and controlled by said piston for subjecting pressure areas on said valves to valve throwing pressures and for intermediately connecting such pressure areas to exhaust through said throwing passages, certain pressure areas on said valves being connectible to exhaust through said distribution passages under the control of said piston, and auxiliary exhaust means controlled by said valves for con-

necting said bores at the inner sides of said valves to atmosphere.

15. In a pressure fluid motor, the combination comprising a cylinder, a piston reciprocable in said cylinder, and fluid distribution means for the motor including a piston-controlled cylinder exhaust, means providing a pair of alined valve-receiving bores, fluid distribution passages leading respectively from said bores to the opposite ends of said cylinder, a pressure fluid supply, a pair of cooperating fluid distributing valves arranged in said bores, said valves being relatively movable and adapted to abut one another in certain positions thereof, said valves cooperating to provide an internal fluid supply chamber therein, means for connecting said supply in constant communication with said internal chamber including a fluid conducting tube extending centrally within said valves, and said valves controlling the flow of pressure fluid from said chamber to said passages respectively, means for throwing said valves into their different operating positions including passages communicating with said bores and controlled by said piston for subjecting pressure areas on said valves to valve throwing pressures, certain pressure areas on said valves being connectible to exhaust through said distribution passages under the control of said piston, and auxiliary exhaust means for a pressure area on one of said valves for substantially delaying the throwing of said latter valve.

16. In a pressure fluid motor, the combination comprising a cylinder, a piston reciprocable in said cylinder, and fluid distribution means for the motor including means providing a pair of alined valve receiving bores, fluid distribution passages leading respectively from said bores to the opposite ends of said cylinder, a pressure fluid supply, a pair of cooperating fluid distributing valves arranged in said bores, said valves being relatively movable and adapted to abut one another in certain positions thereof, said valves controlling the flow of pressure fluid from said supply to said passages respectively, means for throwing said valves into their different operating positions including throwing passages communicating with said bores and controlled by said piston for subjecting pressure areas on said valves to valve throwing pressures, and means for venting a portion of the fluid delivered to at least one of said areas to effect valve throwing, to delay valve throwing.

17. In a pressure fluid motor, the combination comprising a cylinder, a piston reciprocable in said cylinder, and fluid distribution means for the motor including means providing a pair of alined valve receiving bores, fluid distribution passages leading respectively from said bores to the opposite ends of said cylinder, a pressure fluid supply, a pair of cooperating fluid distributing valves arranged in said bores, said valves being relatively movable and adapted to abut one another in certain positions thereof, said valves controlling the flow of pressure fluid from said supply to said passages respectively, means for throwing said valves into their different operating positions including throwing passages communicating with said bores and controlled by said piston for subjecting pressure areas on said valves to valve throwing pressures, and means associated with said pressure areas for venting a portion of the throwing pressure fluid delivered thereto.

18. In a pressure fluid motor, the combination

comprising a cylinder, a piston reciprocable in said cylinder, and fluid distribution means for the motor including means providing a pair of aligned valve receiving bores, fluid distribution passages leading respectively from said bores to the opposite ends of said cylinder, a pressure fluid supply, a pair of cooperating fluid distributing valves arranged in said bores, said valves being relatively movable and adapted to abut one another in certain positions thereof, said valves controlling the flow of pressure fluid from said supply to said passages respectively, means for throwing said valves into their different operating positions including throwing passages communicating with said bores and controlled by said piston for subjecting pressure areas on said valves to valve throwing pressures, means for interconnecting said areas, and means for venting a portion of the throwing fluid passing to said areas to effect valve throwing, to delay valve throwing.

19. In a pressure fluid motor, in combination, a cylinder, a piston reciprocable in said cylinder, and fluid distribution means for the motor including means providing a pair of aligned valve receiving bores, a pair of cooperating fluid distributing valves arranged in said bores, said valves being relatively movable and adapted to abut one another in certain positions thereof, a pressure fluid supply, a plurality of passages leading from each bore to the cylinder, said plurality of passages from one bore opening into one half of the cylinder and said plurality of passages from the other bore opening into the

other half of the cylinder, at least one passage from each end serving as a distribution passage and each of said passages conducting fluid to an area on one of said valves to exert a pressure thereon effective in the movement of the latter, and passage means opening from at least one of said bores to atmosphere for discharging a portion of the fluid delivered through one of said first mentioned passage means to delay valve movement by such fluid.

5 20. In a pressure fluid motor, in combination, a cylinder, a piston reciprocable in said cylinder, and fluid distribution means for the motor including means providing a pair of aligned valve receiving bores, a pair of cooperating fluid distributing valves arranged in said bores, said valves being relatively movable and adapted to abut one another in certain positions thereof, a pressure fluid supply, a plurality of passages leading from each bore to the cylinder, said 10 passages from one bore opening into one half of the cylinder and said passages from the other bore opening into the other half of the cylinder, at least one passage from each end serving as a distribution passage and each of said passages 15 conducting fluid to an area on one of said valves to exert a pressure thereon effective in the movement of the latter, and passage means opening from said bores to atmosphere for discharging a portion of the fluid delivered through one of said first mentioned passage means to delay valve movement by such fluid.
